[57] ABSTRACT

A partition, e.g. for use in railway coaches, in which supporting pillars are lined with facing panels, each of the pillars being constituted by two substantially U-shaped profiled sections disposed in opposite directions to one another. The web portion of at least one of the profiled sections, which web brings together its two flanges, extends beyond the flange located inside the other profiled section and does duty as a stop vis-a-vis the neighbouring flange of said profiled section.

PARTITIONS

The present invention relates to partitions.

The partitions which separate from one another the compartments of railway coaches, are currently manufactured of wood or composites, and possibly lined with facing panels on their external faces. The baggage racks which are assembled on these partitions, comprise a fixing plate attached to a wall plate. Two wall plates, each carrying a baggage rack with its fixing plate, are located at either side of a partition and attached to one another by bolts or similar elements, which pass right through the partition. Mirror frames or photograph frames are often provided and these frames are attached to the external faces of the partitions.

The fixing plates and the wall plates, as well as the possible frames for photographs or mirrors, project above the external faces of the partitions, and this constitutes a source of possible danger and detracts from the aesthetic appearance. It is virtually impossible to recess heating pipes and electrical conductors into a partition, and floor vibrations are transmitted to the partitions and to the seats attached to them.

The object of the present invention is to provide a partition which can in particular be used as a compartment partition in railway coaches, and which overcomes the aforesaid drawbacks.

The partition in accordance with the invention is formed by supporting pillars or uprights lined with facing panels, and is characterised in that each of the pillars or uprights is constituted by two substantially U-shaped profiled sections disposed in opposite directions to one another and fitted together, the web portion of at least one of the profiled sections, which web brings together its two flanges, extending beyond the flange located inside the other profiled section and doing duty as a stop vis-a-vis the neighbouring flange of said profiled section.

Thanks to this arrangement, between the internal flange of the first profiled section and the adjacent flange of the second profiled section, which latter flange constitutes one of the external faces of the upright, a space is left in which there can be fitted the end of a supporting bracket, an opening being provided for this purpose, in one of the external faces of the upright. This bracket-end can be fixed to the upright for example using one or more bolts, without it being necessary to provide fixing plates or wall plates; because it is secured encastre in the upright, it cannot pivot and said encastre fixing is of course even more secure if said end passes through both external faces of the upright. Where a bracket is provided at either side of the partition, the two brackets can be independent of one another or may, on the other hand, be constituted by a single component whose centre section is located encastre in the upright. Since the bolts are concealed by the facing panels, no fixing element for the bracket or brackets, is visible and external faces of the partition can be perfectly smooth.

The partition in accordance with the invention is much lighter than an ordinary partition because of the space which exists between the facing panels. This space may, if required, contain a sound-damping material such as glass wool and can also be utilised for the laying of fluid-transfer lines or electrical conductors. The sound-damping will be still further improved if the bottom part of each upright is fitted with a shock-absorber foot of elastomeric material. The facing pan-

els can be adapted to accord with the intended application and the desired decoration.

Where the partition is to have one or more frames for mirrors or photographs, these frames can be force-fitted in the facing panels. In accordance with a supplementary feature of the invention, the panel will comprise, opposite the opening designed to receive the frame, an internal profile designed to support said frame and the latter can be maintained in position by a surround force-fitted in said opening. The frame and its fixing means thus project hardly at all above the external face of the partition.

As indicated hereinbefore, the invention can be applied in particular to the partitions between the compartments of railway coaches. It is clear, however, that the invention has a more general application too and could be applied in all situations where a partition is required which is equipped with brackets, these being designed for example to support shelves.

In the following, by way of non-limitative example, an embodiment of a partition in accordance with the invention has been described in the context of its applications to a railway coach, with reference to the attached drawings in which:

FIG. 1 is a perspective view of a partition in accordance with the invention, partially cut away;

FIG. 2 is a transverse sectional view through a supporting upright;

FIG. 3 is a view similar to that of FIG. 2, at the location of a bracket;

FIG. 4 is a view in longitudinal section, of an upright at the location of a bracket;

FIG. 5 and 6 are views similar to FIG. 4 and show two variant embodiments;

FIG. 7 illustrates how an upright can be attached to the top part of a room;

FIG. 8 illustrates an elevational view of a partition for a railway coach compartment;

FIG. 9 is a section on the line IX-IX of FIG. 8; and FIG. 10 illustrates a detail of an upright.

The partition shown in FIGS. 1 to 3 is constituted by supporting pillars or uprights faced with decorative panels and interconnected by spacers.

Each of these supporting uprights is constituted by two profiled sections 1 having a substantially U-shaped cross-section. The flange 1a is slightly longer than the flange 1b with which it is parallel, this in fact by a distance substantially equal to the thickness of the profiled section (FIG. 2). The portion 1c, or web of the profiled section, which links the two flanges 1a and 1b, projects slightly beyond the shorter flange 1b, as shown in 1d. The two profiled sections are arranged in opposite directions in order to constitute a pillar of substantially rectangular cross-section, an opening 2 thus being formed between the flange 1a of each of the profiled sections and the adjacent flange 1b of the particular other. The two profiled sections 1 are attached to one another by welding for example.

The base of each upright rests upon the floor 3 through the medium of a footing or plinth of elastomeric material, in which said base is inserted.

Each of the openings 2 is traversed by a component 5 projecting at either side of the pillar and constituting a double bracket. The face 1d of each of the profiled sections is to this end provided with an aperture 6 communicating with said associated opening.

The brackets 5 are attached to the uprights for example by means of nuts 7 which have previously been fixed to the internal face of the flange 1b., and screws 8 which co-operate with said nuts (FIG. 3). Equally, a single bolt passing through the whole of the upright could be used to achieve the simultaneous attachment thereto of the two double brackets.

The assembly of the uprights is lined with two decorative panels 9a and 9 which are applied on the portions 1c of the profiled sections 1 and contain apertures 10 which pass the brackets 5. A sound-damping material 11, for example glass wool, can be arranged in the space defined between the panels 9a and 9b by the pillars.

It will be appreciated from the preceding description that the finished partition has a relatively low weight and is a good acoustic insulator, vibrations from the floor 3 not being transmitted to it. The attachment of the brackets 5 is completely invisible and does not necessitate any projecting part on the external faces of the partition, these latter faces are perfectly smooth.

Instead of being made as a single component, each double bracket can be constituted by two separate brackets 5a and 5b. In this case, that portion of each bracket which is located in the opening 2 has a lower height, in fact half the normal height if the two brackets 5a and 5b are identical (FIGS. 4 and 5). This bracket section may pass through only one of the external faces of the pillar, the aperture 6 then having a height equal to this section (FIG. 4). It is preferable, however, where the weight carried by the bracket is to be fairly high, for this section to pass through both external faces of the pillar, the aperture 6 then having the same height as the brackets and being partially traversed by the bracket 5a and partially by the bracket 5b (FIG. 5).

Self-evidently, the partition may be fitted with brackets on only one of its faces (FIG. 6). That portion of the bracket which is located in the opening 2 may pass through only one of the external faces of the upright, as shown in FIG. 6, or may for that matter pass through both faces thereof.

In order to maintain the top part of the partition in position, the top framing of the room in which the partition is set up, may comprise a turned-down sheet metal portion 12 equipped with lugs 12a each of which is engaged in a block of elastomeric material 13 arranged in the top end of an upright 1, the assembly being fixed to said upright by screws 14 and nuts 15 (FIG. 7).

FIGS. 8 to 10 illustrate the application of the invention to railway coaches.

Here, the partition is arranged between two compartments. Seats 17 above which there is a stick rack 18, are arranged at either side of the partition. The brackets 5 are used to carry a luggage rack 19.

The facing panels provided on each side of the partition number 3 in this case, which are arranged one above the other. The bottom panel 20a is located at its bottom end by a profiled section 21 attached to the uprights. The top edge of this panel is located a little below the top edge of the seats 17; the panel is therefore concealed and its external appearance is therefore unimportant.

The panel 20a is assembled, by a profiled section 22 of H-section, with flanges of unequal length, to a panel 20b which extends substantially up to the ceiling. The top panel 20c is engaged through its top edge, in a pro-

filed section 23 attached to the pillars 1. The bottom edge of the panel 20c and the top edge of the panel 20b are both maintained in position by a profiled section 24 which forms a protective bar. This profiled section is attached to the uprights 1 by stops 25 which are inserted into the profiled section and each comprise a lug 25a engaging in an aperture 26 in the external face of the pillar, where it is locked by downward displacement.

Assembly is carried out by successively fitting the panel 20a, the panel 20b, the profiled section 24 and the panel 20c which secures the stops 25 in position, and finally by fitting the profiled section 23. Inversely, the removal of the latter profiled section, enables the various panels to be attached.

The panel 20b can contain openings 27 designed to take the frames 28 of mirrors or photographs. These frames are carried by profiled sections 29 fixed to the internal face of the panel 20b and are held in position by a surround 30 of T-shaped cross-section, force-fitted in the opening 27.

It will be seen therefore that there is no visible fixing and that the mirrors or photographs which are fitted are located substantially in the same plane as the panels 20b; the space defined between the panels and possibly containing a sound-damping material 11, can also be used for the laying of heating pipes or again for electrical conductors to supply lights above the seats 17.

It goes without saying that the invention is in no way limited to the embodiment described and illustrated here but extends instead to all the possible variant embodiments.

What I claim as my invention and desire to secure by Letters Patent of the United States is :

1. A partition constituted by supporting pillars or uprights lined with facing panels, wherein each of the pillars or uprights is constituted by two profiled substantially U-shaped sections facing in opposite directions and fitted into one another, each of which sections has a web and two flange portions, the web portion of at least one of the profiled sections, which links the two flanges thereof, extending beyond a web which is disposed inside the particular other profiled section and acting as a stop for the neighbouring flange of said other profiled sections so that a space is formed between the internal flange of the first profiled section and the adjacent flange of the second profiled section, which latter flange forms one of the external faces of the upright, and wherein at least one supporting bracket is disposed in said space, fixed to the upright by fixing means engaging an aperture provided in at least one of the external faces of the upright.

2. A partition as claimed in claim 1, wherein the flange in the profiled section which is located at the side at which the web is extended, is shorter than the other flange by a distance substantially equal to the thickness of said web.

3. A partition as claimed in claim 1, wherein the supporting bracket is engaged in both external faces of the upright.

4. A partition as claimed in claim 1, wherein the bracket comprises two portions, each of which projects away from one of the external faces of the upright.

5. A partition as claimed in one of the claims 1, wherein two brackets, each of which projects beyond one of the external faces of the upright, comprise a portion of reduced height, and wherein the two ends of the

two brackets are engaged in the same opening in the upright.

6. A partition as claimed in claim 1, wherein the bottom part of each upright has a shock-absorbing footing or plinth of elastomatic material, and wherein a sound-damping material is arranged between the two facing panels.

7. A partition as claimed in claim 1, where the top part of the room is in which the partition is set up, comprises a down-turned portion equipped with lugs each of which is engaged in a block of elastomeric material disposed at the top end of an upright, the assembly being fixed to this upright.

8. A partition as claimed in claim 1, in which the facing panel comprises at least one opening for the frame of a mirror or photograph, wherein the panel is provided, at the location of the opening, with an internal profiled section serving to support the frame; and in

that the latter is held in position by a surround force-fitted in said opening.

9. A railway coach including a partition as claimed in claim 1.

10. A railway coach as claimed in claim 9, wherein each facing panel comprises a first bottom panel extending substantially up to the top part of the seats and whose bottom edge is held in position by a profiled section attached to the uprights, a second intermediate panel assembled to the first by a profiled section and a third, top panel whose top edge is held in position by a profiled section attached to the uprights, the bottom edge of said top panel and the top edge of the intermediate panel being located by one and the same profiled section which is attached in detachable manner to the uprights.
